2,622,897

BOOK JACKET

George Zenick, Los Angeles, Calif., assignor to
The Patent and Licensing Corporation, New
York, N. Y., a corporation of Massachusetts

Application June 17, 1949, Serial No. 99,737

2 Claims. (Cl. 281—20)

1

This invention relates to a pocket or jacket for books and magazines and has particular reference to a collapsible device of this type.

Of the great number of magazines and other periodicals, literary, scientific as well as professional, published and distributed year after year, many are of permanent value to the subscriber or recipient and are stored away on shelves or in drawers for reference. When needed, at times urgently, they are generally found only after a prolonged search besides, being unprotected, may become so crumpled, dogeared and soiled during the laborious handling in searching and storing them they gradually become difficult to use if not entirely useless.

It is in view of the foregoing the general object of my invention to provide a simple and inexpensive book jacket of attractive appearance, within which one or a specified number of such publications may be stored so as to provide continuing series of numbered or otherwise marked volumes which, when properly arranged on the bookshelf, take up a minimum of space, can be found by a mere glance, and will protect their contents over indefinite periods of time.

It is a further object of the invention to provide a collapsible book jacket. By this is meant a device which is produced from a simple blank which is so shaped and marked that it may quickly be manually folded and refolded by the user or his assistant, without having to resort to the use of adhesives or any other binder, to form the finished product.

These and other objects of the invention, as well as the many advantageous features thereof will be better understood from the following detailed description when taken in connection with the accompanying drawings forming part thereof.

In the drawings:

Fig. 1 is an isometric end view of a book jacket embodying the invention;

Fig. 2 shows the single blank from which the jacket of Fig. 1 is produced;

Figs. 3, 4, 5 are similar isometric projections indicating how the blank is progressively folded; and

Fig. 6 is a cross-sectional side view taken substantially on line 6—6 of Fig. 1.

The blank 1, illustrated in Fig. 2, would ordinarily consist of a single piece of cardboard the outer surface of which may be coated with a covering of fabric, leather or any other more attractive substance. But a plastic or any other suitable substance may, of course, be substituted

2

so long as it is adapted for folding in accordance with the present invention. On this blank are marked, in order to simplify the following description, the parts of the blank forming the side, back and end surfaces of the jacket; the lines 2, 3, represent the edges along which the blank is cut through and the dotted lines indicate the lines along which the various parts are to be folded.

Referring now to Fig. 3, it is noticed that the upper end 5 has been folded on line 6 and the flap 7, laterally extending therefrom, has been folded into registration with folding line 8 marking the dividing line between the left side portion and the back of the jacket. It is important to note that a narrow, slightly flaring slit 9 has been cut into the upper edge of the flap 7.

The lower end 10 is next folded upwardly, as indicated in Fig. 4, whereupon the flap 11, laterally extending therefrom, is bent inwardly to cause the edges of the flaring slit 12 thereof to reach a position of registration with the slit 9 of the flap 7, into which it is caused to enter. The end flaps 13, 14, which extend outwardly from the end portions 5, 10, are then folded inwardly, as indicated in Fig. 4, until they reach the completely folded position of Fig. 5 to form the inner lining for the right side of the finished jacket. Finally the back 15 and the right side position 16 are folded on lines 3 and 17 in the direction indicated in Fig. 5 until they completely cover the interlocked flaps 7, 11, and the right side inner lining flaps 13, 14.

It is now noticed that a marginal strip 18 extends laterally from the right side position 16. This strip is now folded inwardly over the edges 20, 21 of these inner lining flaps more securely to tie the flaps together and so as to provide a smooth, rounded finish along this edge of the jacket.

Similarly, a marginal strip 22 is extended laterally from the left side edges of the ends and left side portion of the blank. This strip was folded over the inner surfaces of these jacket portions, along the line 23, at the time the ends were folded, as best indicated in Fig. 4, to complete a continuous, rounded edge along the entire opening of the jacket. When the end edges 24, 25 of the strip 18 are slightly outwardly flared, it is found that, when pressed in position within the inner corners of the jacket, they will more securely retain the jacket in folded position.

I claim:

1. A jacket for books formed from a single, integral blank and maintainable as a self-sustaining erected unit solely by the inter-engage-

ment of portions of the blank, consisting essentially of a pair of parallel side portions separated by a back member integral with the rear edges of the side portions, end portions integral with one of the side portions said back member and end portions of a width substantially less than said side portions, inter-engaging back-reinforcing portions overlying the back member and integral with the end portions, side-reinforcing portions overlying the other of said side portions and integral with the end portions, a relatively narrow marginal strip of uniform width integral with the outer edges of the end portions and the interposed side portions and co-extensive therewith and folded inwardly of the jacket to overlie substantially less than a half of each of the said end portions and interposed side portion, and a second marginal strip integral with the outer edge of the second-named side portion, said second-named marginal strip having substantially the same width as said first-named marginal strip and having a free outer edge and free outwardly-flared side edges and being folded inwardly into engagement with the first-named marginal strip folded inwardly of 25 the end portions, whereby said jacket is retained in assembled position for use but is readily collapsible for storage and whereby there is formed a book jacket closed on five sides and open on its most elongated narrow side.

2. A blank for a book jacket adapted to be assembled into a self-sustaining unit solely by the inter-engagement of portions of the blank, consisting essentially of a unitary sheet of foldable material cut and scored to define a pair 35 of side portions separated by a back portion integral with the opposed side edges of said side portions, end portions extending outwardly from the end edges of one of said side portions substantially less than said side portions, inter- 40

engaging flaps adapted to overlie the back portion when the blank is assembled extending from an end edge of each of said end portions, lining flaps adapted to overlie the second-named side portion extending outwardly from the side edge of each of the said end portions, a relatively narrow marginal strip of uniform width extending along the outer edge of the first-named side portion and the adjacent end portions and co-extensive therewith, said marginal strip being substantially less than half the width of each of said first-named side portion and adjacent end portions, and a second marginal strip disposed along the outer edge of the second-named side portion adapted to make frictional engagement with the said first-named marginal strip when the blank is assembled, said second-named marginal strip having substantially the same width as said first-named marginal strip and having a free outer edge and free outwardly-flared side edges and whereby there is formed a book jacket closed on five sides and open on its most elongated narrow side.

GEORGE ZENICK.
